UNITED STATES PATENT OFFICE.

REINHOLD D. SCHOENWETTER, OF BALTIMORE, MARYLAND, ASSIGNOR TO NATIONAL MANUFACTURING COMPANY, OF BALTIMORE, MARYLAND, A CORPORATION OF MARYLAND.

CONVEYER MECHANISM.

Original application filed January 8, 1920, Serial No. 350,186. Divided and this application filed February 7, 1922. Serial No. 534,655.

To all whom it may concern:

Be it known that I, REINHOLD D. SCHOENWETTER, a citizen of the United States, residing at Baltimore, in the State of Maryland, have invented certain new and useful Improvements in Conveyer Mechanism; and I do hereby declare the following to be a full, clear, and exact description of the invention, such as will enable others skilled in the art to which it appertains to make and use the same.

My invention relates to coating machines.

Among the objects of my invention are:—

To provide means for applying a coating 15 of water to a gummed band such as is usually applied to cigars.

To provide means for removing a band from a stack of bands and bringing same into operative relation with the coating 20 mechanism.

To provide means for delivering the band to means for applying the band to the cigar after said band has been coated with water.

To provide means for adjustably varying 25 the time interval between the application of the coat of water to the band and the application of the band to the cigar.

To provide means for operating the various 30 elements of my improved coating machine at the proper times.

To provide simple and effective means for removing the band from each element and delivering it to the next element during the 35 operation of coating the band.

To provide a wetting mechanism capable of operating upon bands that vary greatly in size and shape.

To provide a machine capable of performing 40 the ascribed functions and having a minimum of parts and requiring a minimum of adjustment and care.

This application is a division of my pending 45 application for Letters Patent Serial No. 350,186, filed January 8, 1920 for coating machines.

My improved cigar banding machine consists of a magazine in which the bands are stacked and from which they are removed 50 by an appropriate sheet feeding machine and delivered to a conveyer by which they are brought into operative relation to a coating mechanism which applies moisture or a gum

preparation to said bands, after which a depositor removes the bands from the conveyer and delivers said bands to the band applying mechanism, which applies the bands to the cigars. The cigars are held and controlled by appropriate mechanism forming part of the band applying mechanism and said cigars are also shifted by suitable mechanism from the position in which the band is applied after the operation is completed.

This application is intended to cover the 65 novel features involved in the mechanism which performs the various operations by which the band is transported from the band holding mechanism to the band applying mechanism and coated with water or other 70 material during said transportation.

One combination of elements for carrying out my invention is illustrated in the accompanying drawings, in which:—

Fig. 1 is a plan view of my improved 75 coating machine, the bracket 58 being shown as in section along the line 1—1 in Fig. 6, and the nostril 210 being shown in section along the line 1^a in Fig. 6.

Fig. 2 is a section of the parts shown in 80 Fig. 1 taken along the line 2—2 in Fig. 1, certain of the parts being shown in elevation and not in section, looking in the direction of the arrows.

Fig. 3 is an elevation of the conveyer, 85 one clamp and the depositor, these parts being shown as viewed in the direction of the arrow 3 in Fig. 1.

Fig. 4 is an elevation of the conveyer, showing one clamp thereon and one suction 90 head, the parts being viewed in the direction of the arrow 3 in Fig. 1. This view also shows the suction pump which is not shown in Fig. 1.

Fig. 5 is an elevation of the wetter and 95 operating means therefor, as shown in Fig. 1 when viewed in the direction of the arrow 3 in said figure. In Fig. 5 the reservoir for containing the water is shown but said reservoir is not illustrated in Fig. 1.

Fig. 6 is an elevation of certain of the parts as shown in Fig. 1 when viewed in the direction of the arrow 3 in said figure. This view also shows the upper end of the bracket 58 and the suction head which shifts 105 the bands from the depositor and delivers

them to the band applying mechanism, but the upper end of the bracket 58 and said head are not shown in Fig. 1.

Fig. 7 is a plan view of the pump cylinders and yoke for operating the pistons thereof, the parts being shown as viewed in the direction of the arrow 7 in Fig. 4.

In the drawings:

20 represents the main frame of the machine which is made of any suitable shape for supporting the various mechanisms forming parts of my improved cigar banding machine.

21 is the main shaft of my improved cigar banding machine which is revolvably mounted in suitable bearings, one of which is shown as at 22 and said shaft is revolved in any suitable manner by any suitable source of power.

22 A cam disk 23 is rigidly mounted upon the shaft 21 and a groove 24 is provided in one face of said disk.

23 A roller 25 revolvably mounted upon one end of the bell crank lever 26 is mounted in said groove. The lever 26 is secured upon the shaft 27 and the latter is revolvably mounted in suitable bearings, one of which is shown as at 28.

24 The left hand end of the bell crank lever 26, (see Fig. 4), is connected by the link 29 with the cross head 30 which is rigidly secured upon the ends of the rods 31—31, the latter being slidably mounted in the bearing 32. The rods 31—31 are joined together at the top by the cross head 33, the latter being provided with a clamp 34 in which the suction head 35 is secured. The clamp 34 is so arranged that the suction head may be adjusted vertically as desired.

25 The suction head 35 is formed on a short length of tube to the lower end of which one end of the hose connection 36 is secured. The other end of the hose connection 36 is secured upon a nipple formed upon the

26 pump cylinder 37. The pump cylinder 37 is secured upon the frame 20 by suitable bolts such as 38. A second pump cylinder 39 is also secured upon the frame 20 by suitable bolts such as 40.

27 Pistons 41 and 42 formed integrally with the connecting rod 43 are slidably mounted within the cylinders 37 and 39. The pistons 41 and 42 may be provided with any suitable packing or rings.

28 A yoke 44 is pivotally connected by the bolt 45 to the connecting rod 43 and the other end of said yoke is provided with a slot 46 through which the main shaft 21 extends. Cam rollers 47—47 are mounted

29 upon the yoke 44 and said rollers contact with the face of the cams 48—48, the latter being rigidly secured upon the shaft 21.

30 The cigar bands are supported in a suitable magazine, not shown, and the lowermost band 49 is bowed into the position

shown in Fig. 4 preparatory to its removal from the band magazine.

The operation of the parts hereinbefore described is as follows:

31 The shaft 21 being revolved, the roller 25 is moved by the wall of the groove 24 and brings the suction head 35 upwardly until it contacts with the band 49. One of the cams 48, then moves a cam roller 47 in such a direction as to bring the piston 41 75 from its extreme right hand position, as indicated by the dotted line 50 in Fig. 4, to the position shown in Fig. 4, thus creating a partial vacuum within the cylinder 37. When this occurs the pressure of the 80 atmosphere holds the band 49 against the top of the suction head 35, the side of the groove 24 then acts upon the roller 25 to move the suction head 35 downwardly to the position shown by full lines in Fig. 4 85 in which position the suction head normally rests in order to permit the band at 49^a to be delivered to the conveyer 51. The conveyer 51 comprises a disk 52 provided with a groove bearing 53 which is revolvably 90 mounted upon a plurality of steel balls such as 54 and the latter are supported in the groove bearing 55 formed in the index plate 56 which is secured by the bolts 57 to the bracket 58. The bracket 58 is secured upon the frame 20 by bolts such as 59. The bolt 60 is secured in the index plate 56 and a disk 61 secured upon the top of said bolt and bearing against the top of the disk 52 serves to prevent displacement of the disk 95 52 from the steel balls 54. A ring 62, preferably formed of aluminum, and having a chamfered edge as at 63 is secured in any approved manner upon the disk 52.

I preferably employ aluminum for forming the ring 62 because of its freedom from corrosion since this ring becomes moistened by the wetting mechanism during the ordinary operation of the machine.

32 A plurality of brackets each comprising a base 64 and a pair of ears such as 65—65 is secured upon the disk 52. A bearing pin 66 is revolvably mounted in each pair of ears 65—65 and the ends of said pin are rigidly mounted in the ears 67—67 formed integrally with the clamp 68. A spring such as 69 mounted between the ears 65—65 upon the pin 66 serves to keep each clamp normally in the position shown in Fig. 2. Each clamp 68 is provided with a tappet portion such as 70 and with an indurated fibre nose such as 71 secured upon the clamping end.

The periphery of the disk 52 is formed with a plurality of teeth such as 72, the teeth being of the contour such as is ordinarily employed in the ordinary Geneva wind.

The pinion 73 having a single tooth 74 is mounted upon the shaft 75 and the latter 120

is revolvably mounted in a suitable bearing formed within the bracket 58. A bevel gear 77 is mounted upon the lower end of the shaft 75 and a bevel gear 78 meshes therewith. The bevel gear 78 is mounted upon the shaft 79 and the latter is revolvably mounted in suitable bearings one of which is shown upon the bracket 58. The bevel gear 80 is mounted upon the shaft 79 and 10 meshes with the bevel gear 81 secured on one end of the shaft 82, the latter is mounted in suitable bearings (not shown) and the bevel gear 83 is mounted upon the other end thereof. The bevel gear 83 meshes with the bevel gear 84 and the latter is mounted upon the main shaft 21.

The means for operating the clamps 68 to receive a band will now be described:—

The roller 85 is revolvably mounted in the fork 86 and the latter is vertically slidable within the bracket 87, an adjusting nut 88 being mounted upon the fork 86 in order to limit the vertical movement thereof.

The clamp opening lever 89 is pivotally mounted upon the pin 90 and the latter is secured in the bracket 87. The bracket 87 is secured upon the frame 20 by bolts. The lever 89 is provided with a groove in which is slidably mounted the wood block 92 and 25 the metallic pin 93 is fixed in said block. The pin 93 extends through the slot 94 formed in the bracket 87 into a suitable hole provided in the fork 86. A spring 95 is secured at one end to the lever 89 and at the other end to the bracket 87 and serves to move the lever from the position shown by full lines in Fig. 4 to the position shown by dotted lines in said figure whenever the nose 71 is to be lifted from the aluminum ring 62. 30 The lever 89 is provided with a bearing 96 on its left hand end (see Fig. 4) and the sleeve 97 is provided with a cylindrical portion which is revolvably mounted in said bearing. A rod 98 slides freely through the sleeve 97 and the lower end of said rod is provided with a bearing 99 which is revolvably mounted upon the pin 100 secured in the cross head 33. Adjusting nuts such as 101 serve to adjust the operation of the lever 89.

The means for moistening the bands with water or coating them with a gum preparation will now be described:—

The cam disk 102 is mounted upon the shaft 21 and bolted to the cam disk 23. A cam groove 103 is provided in the disk 102 and the roller 104 is revolvably mounted on the upper end of the lever 105 and the latter is pivotally mounted on the pin 106 secured in the bracket 107 which is secured to the frame 20 by bolts such as 108. The lower end of the lever 105 is pivotally connected to one end of the link 109, the other end of which is pivotally connected to the lower end of the lever 110. The link 109 is pro-

vided with a clevis on each end by means of which its length may be adjusted. The lever 110 is rigidly secured to the shaft 111 and the latter is revolvably mounted in suitable bearing brackets one of which is shown at 112 in Fig. 5 and is secured to the frame 20 by means of bolts such as 113. The lever 114 is also secured to the shaft 111 and the sleeve 115 is secured to the end of said lever. The lower member of the universal joint 116 is revolvably mounted in the sleeve 115 and the upper member of said joint is connected to the link 117 which extends through the hole 118 provided in the frame 20 and said link is pivotally connected at its upper end to one end of the bell crank lever 119, the latter being pivotally mounted on the bracket 120. The bracket 120 is revolvably mounted upon the lower end of the bolt 60.

It is to be noted that the upper end of the link 117 is in substantial alignment with the axis of the bolt 60; consequently, as the bracket 120 is revolved, as hereinafter explained, no motion of the lever 119 is effected. It is also evident that by reason of the fact that the lower end of the universal joint 116 is revolvably mounted in the sleeve 115, the bracket 120 may be freely turned about the bolt 60.

The upper end of the bell crank lever 119 is pivotally connected to one end of the arm 121 which is formed integrally with the sponge holder 122. A pin 123 is mounted in the arm 121 and the roller 124 is revolvably mounted upon the end of said pin. The roller 124 extends into the recess 126 provided in the arm 127, the switch 128 is secured upon the inner end of the shaft 129, the latter being revolvably mounted in a suitable bearing provided in the arm 127 and an arm 130 is secured upon the outer end of said shaft. A spring 131 secured at one end of said arm and at the other end to the arm 127 serves to normally keep the switch 128 in the position shown in Fig. 2. In Figs. 1 and 2, the middle portion of the spring is omitted for the sake of clearness. The switch 128 is shaped so that when the roller 124 moves in a counter-clockwise direction around said switch, (see Fig. 2), as herein, after explained, it will be guided by the wall of said recess and the face of said switch from the position marked 132 in said figure to the position marked 133 in said figure, without producing any movement of said switch. As said roller moves from the position marked 133 to the position marked 134, the switch 128 will be lifted and the spring will bring said switch to the position shown by full lines in Fig. 2, when the roller has reached the position shown dotted at 134.

During this last-described movement of the roller 124, it will be guided by the wall of the recess 126 and the lower face of the switch 128. During the movement of the

roller 124 from the position shown at 134 to the position shown at 135, the roller will be guided by the wall of the recess 126 and by the edge 136 of the plate 137, said edge 5 bearing upon the pin 123. When the roller moves from the position shown at 135 to the position shown at 132, it will be guided by the face of the switch 128 and by the edges 136 and 138 of the plate 137, said edges 10 bearing against the pin 123.

From the position shown at 132, in a counter clockwise direction, to the position shown at 135, the plate 137 is provided with an edge 139 which follows the contour of 15 the wall of the recess 126 and projects sufficiently inside of said wall to just clear the pin 123 when the roller 124 is moving around said wall. The projecting edge 139 is provided on this portion of the plate in 20 order to extend over the face of the roller 124 adjacent to the arm 121 and the edges 136 and 138 have a like relation to said face, this arrangement of the plate with reference to said roller insuring that the arms 121 and 25 127 shall move together when the arm 127 is revolved around the bolt 60, as hereinafter explained. The arm 127 is revolubly mounted upon the bolt 60 between the bracket 120 and the index plate 56. The arm 127 is 30 provided with a boss 140 in which is slidably mounted the index pin 141 normally kept in the position shown in Fig. 2 by the spring 142 and capable of movement downwardly from said position by the head 143 secured 35 to the lower end of said pin. The upper end of the pin 141 may be introduced within any one of the index holes 144 by moving the head 143 downwardly and shifting the arm 127 until the upper end of said pin is 40 in alignment with said hole, thus locking the arm 127 in any desired position, for a purpose hereinafter explained.

The reservoir 145 is secured at the upper 45 end of the pipe 146 and the lower end of said pipe is secured in the frame 20 and extends through said frame, a hose connection 147 being secured at one end of said extension and the other end of said hose being secured to one end of the pipe 148 mounted 50 upon the link 117. The hose 149 is secured to the lower end of the pipe 148 and the upper end of said hose is secured to the sponge holder 122.

The depositor which removes the bands 55 from the conveyer after the same have been wetted and delivers them to the suction head that transfers them to the band applying mechanism will now be described:

A cam disk 150 is secured upon the shaft 60 21 and said cam disk is provided with a groove 151 in which is mounted the cam roller 152, the latter being revolubly mounted upon the pin 153, the pin 153 being secured in the lever 154 which is mounted at 65 its lower end upon the pin 155 secured in

the bracket 156, and the latter is secured upon the frame 20 by cap screws 157.

A link 158 is pivotally connected at one end to the upper end of the lever 154 and the other end of said link is pivotally connected 70 to one arm of the bell crank lever 159.

The link 158 is provided with a clevis at its right hand end (see Fig. 1) by means of which the length of said link may be adjusted. At its left end the link 158 comprises the spring case 160 in which is mounted the spring 161 against which bears the left face of the enlarged end 162 formed on the rod forming the body of said link. A spring 163 bears against the right face of 80 said enlarged end and a thimble 164 threaded within the case 160 serves to produce any desired pressure of the springs 161 and 163 upon the enlarged end 162.

The lever 159 is formed integrally with 85 the boss 165 and the latter is revolubly mounted upon the sleeve 166, the lower end of which is secured in the frame 20. The nuts 167 at the upper end of said sleeve prevent displacement of the boss 165 thereon, 90 and nuts 168 at the lower end of said sleeve secure the latter in the frame 20. The fixed member 169 of the depositor clamp is secured at the end of the lever 159, as shown in Figs. 1 and 3. 95

The member 169 may be of any suitable shape such as is shown in Figs. 1 and 3, that will adapt it to form one member of the clamp for taking the bands from the conveyer and delivering them to the suction 100 head, and cooperating with said member there is a movable member 170 of said clamp which is shaped to cooperate with the fixed member in moving the bands as just explained. Said movable member is pivoted 105 as at 171 upon a riser 172 provided upon the end of the lever 159. A groove 173 is formed in the depending portion 174 of the member 170 and the roller 175 is mounted in 110 said groove. The roller 175 is mounted upon a pin secured in the upper end of the arm 176 and the latter is secured upon one end of the shaft 177 which is revolubly mounted in the riser 172 and ear 178 formed upon the lever 159 and the lever 179 is secured upon the other end of said shaft. The free end of the lever 179 rests upon the push rod 180 which is slidably mounted coaxially with the sleeve 166, the lower end of the rod 180 rests upon the end of the lever 181 115

which is secured upon the shaft 182 and the latter is revolubly mounted in the bearing bracket 183 secured to the frame 20 by bolts such as 184. The lever 185 is also secured upon the shaft 182 and extends upwardly 120 through a suitable hole provided in the frame 20, and the upper end of said lever is pivotally connected to one end of the link 186, the other end of which is pivotally mounted upon the pin 187 secured in the 130

lever 188, the latter being pivotally mounted upon the pin 155. A roller 189 revolvably mounted upon a pin at the upper end of the lever 188 extends into the cam groove 190 formed in the cam disk 191 and the latter is rigidly secured upon the shaft 21.

The means for operating the suction head which removes the bands from the depositor and delivers them to the band applying mechanism will now be described:

The shaft 192 is revolvably mounted in a suitable bearing provided in the upper end of the bracket 58 and a gear wheel 193 is rigidly secured upon said shaft. The tooth periphery of said gear meshes with a gear belonging to a part of my improved cigar banding machine not included in the present application. The bevel gear 194 is mounted upon the shaft 192 and meshes with the bevel gear 195 which is mounted upon the upper end of the shaft 75. On one side of the gear wheel 193 there is provided a cam groove 196 in which is mounted the roller 197 and the latter is revolvably mounted upon a pin in one end of the lever 198. The lever 198 is secured to the shaft 199 and the lever 200 is also secured to said shaft. The clamp 201 is pivoted to the left end of the lever 200 (see Fig. 6), and the clevis 202 is adjustably secured in said clamp. The clevis 202 is connected to the cross head 203 and the latter is secured to the guide rods 204 and 205, both of which are mounted to slide freely vertically in suitable bearings forming part of the bracket 58. The rod 204 is slidably mounted in any suitable bearing at its lower end and the rod 205 is secured at its lower end to the yoke 206, the prongs of which are slidably mounted in suitable grooves 206^a—206^a formed within the bracket 207 which is secured to the bracket 58 in any approved manner. The yoke 206 is provided with a nipple 208 to which one end of the hose 209 is secured, the other end of said hose being attached to a nipple formed upon the pump cylinder 39. The nipple 208 communicates with a hole in the nostril 210 formed on the lower side of the yoke 206.

In order to provide for non-interference of the clamps upon the conveyer when a band is being removed by the depositor from the conveyer, the following instrumentalities are provided:

The cam 211 is secured upon the shaft 75 and the roller 212 bears against the face of said cam. The roller 212 is revolvably mounted upon a pin secured in the lever 213, the latter being revolvably mounted upon the pin 214 secured in the bracket 215 which is secured to the bracket 58 in any approved manner. Upon a suitable pin in the end of the lever 213 there are revolvably mounted three rollers 216, 217 and 218 which are so located as to be brought into contact, as here-

inafter explained, with three of the tappets 70. In order to restore the lever 213 to the position shown in Fig. 1 after each displacement therefrom by the cam 211, the spring 219 is provided, one end of which is secured to the bracket 58 and the other end of which is secured to the lever 213.

The operation of my improved coating machine is as follows:

As before explained, the cigar band 49 (see Fig. 4), is moved by the suction head 35 in which there is a partial vacuum from the position shown dotted in said figure, in which position it is the lowermost band in the band magazine, to the position shown at 49^a in said figure. During the movement of the band 49, as just described, the cam groove 24 operating through the roller 25 and connected parts will keep the lowermost nut 101 from contact with the sleeve 97 and thus, the spring 95 will force the roller 85 down upon the tappet 70 and lift the nose 71 against the pressure of the spring 69 so that the band 49 may be brought down against the ring 62. Shortly after this occurs, the lowermost nut 101 strikes the sleeve 97 and moves the clamp opening lever 89 to the position shown by full lines in Fig. 4, thus removing the roller 85 from contact with the tappet 70 and allowing the spring 69 to bring the nose 71 down upon the band at 49^a.

It is to be understood that during the motion of the suction head 35 and clamp opening lever 89, the tooth 74 of the pinion 73 will be moving through that part of its arc of motion in which it will be out of contact with a tooth 72 on the conveyer 51 and thus, said conveyer will remain motionless.

As soon as the band is secured between the clamp 71 and the ring 63 one of the cams 48 moves the right hand roller 47 toward the right and moves the piston 41, towards the right thus terminating the partial vacuum within the cylinder 37 and releasing the suction of the head 35 upon the band. The tooth 74 moving in a counter clockwise direction (as shown in Fig. 1), then intermittently rotates the conveyer 51 in a clockwise direction until the band is over the sponge 220. When this occurs, the roller 124 will be in the position shown at 135 in Fig. 2. The wall of the cam groove 103 acting through the roller 104 and connected parts then moves the roller 124 from the position 135 to the position 132, thus bringing the sponge 220 into contact with the lower side of the band, and during the motion of the roller 124 from the position 132 to the position 221, the sponge will be moved approximately horizontally in contact with the lower side of the band. The roller 124 will then move downwardly and toward the right to again reach the position 135, and during this latter movement, the switch 130

128 will be lifted in order to permit the roller to pass and will then be forced downwardly by the spring 131 to the position shown in Fig. 2, thus preventing any return 5 of the roller 124 along the lower side of the recess 126 when it is next operated.

It is to be noted that water is kept in the reservoir 145 up to about the level of the line 222 in Fig. 5 and as the sponge is 10 moved, as just described, the sponge holder 122 will be brought slightly below said level, and consequently, the water passing through the hose 147 and 149 and the tube 148 will 15 wet the lower side of the sponge 220 and keep it moist.

The conveyer 51 is then rotated intermittently, as already described, until the moistened band is brought into position to be grasped by the clamping members of 20 the depositor. When the band has reached this position, the wall of the cam groove 151 operating upon the roller 152 and connected parts moves the depositor from the position shown in Fig. 1 to the position it will 25 occupy when the clamping end of the fixed member of the clamp 169 is in the position shown by dotted lines in said figure.

During the motion of the depositor, as just described, the wall of the cam groove 30 190 acting through the roller 189 and connected parts upon the movable member 170 of the depositor clamp normally keeps the latter raised from the fixed member 169; consequently, when the conveyer 51 is 35 moved forwardly, the band held in the corresponding clamp on the conveyer is introduced between the fixed and movable members of the depositor clamp and the conveyer then comes to rest. The cam groove 40 190 acting through the roller 189 and connected parts will move the end of the lever 181 downwardly and the spring 223 will move the lever 179 and the push rod 180 downwardly. The pressure of said spring 45 195 acting through the roller 175 upon the wall of the groove 173 will bring the movable member 170 down against the band.

It is to be noted by reference to Fig. 1 that the band at 49^b will extend crosswise of 50 the clamping portions of the fixed and movable members of the depositor clamp and that said portions will be applied to said band near the centre of the latter, thus avoiding contact with the wetted portion 55 thereof 224.

The wall of the cam groove 151 acting through the roller 152 and connected parts then moves the depositor from the position in which the clamping end of the fixed member 169 is shown dotted in Fig. 1 to the position shown by full lines in said figure in order to bring the band into operative 60 65 relation with the nostril 210.

Previous to the motion of the depositor, 65 as just described, the face of the cam 211

acting through the roller 212 and connected parts brings the rollers 216, 217 and 218 into contact with three of the tappets 70, thus raising three of the noses 71 in order to release from the conveyer clamp the 70 band that has just been gripped by the depositor clasp, and raising the next two noses in a clockwise direction so as to permit the free passage under same of the end of the band that has just been released. 75

It is to be noted that the rollers 216, 217 and 218 are of different sizes and this variation in size is provided to compensate for the angular position of the lever 213 with reference to the tappet 70 and insures that 80 the three noses 70 will be raised equal distances above the ring 63.

It is desirable to be able to vary the time interval between the instant at which the sponge 220 is applied to the band and the 85 instant at which the band is delivered to the conveyer, and the operation of the parts by which the variation in said time interval is obtained is as follows:—

It is to be noted that the suction head 35 90 delivers the band to the conveyer clamps in a fixed position and that said bands are carried in a clockwise direction (see Fig. 1) by the conveyer to the position in which the sponge 220 is applied thereto. When the 95 sponge 220 is in the position shown in said figure, the shortest time interval allowed will elapse between the instant at which it is applied to the band and the instant at which 100 said band is delivered to the depositor. It 105 may be desired to vary this interval owing to a variation in the hydroscopic state of the atmosphere, the temperature thereof, the nature and consistency of the gum upon the bands, or other factors which might produce 110 a variation in the time required to secure a proper softening of the gum. 115

This is accomplished by applying the fingers to the head 143, applying the index pin 141 downwardly, and moving the arm 127 in a counter clockwise direction and then allowing the index pin 141 to enter the appropriate hole of the series of index holes 144, thus increasing the time interval as desired. 120

It is to be noted that when the arm 127 is moved as just described, the arm 121, which carries the sponge holder, will be moved in unison therewith on account of the relation between the roller 124 and the plate 137 as 125 hereinbefore described.

When the depositor reaches the position shown by full lines in Fig. 1, the wall of the cam groove 196 acting through the roller 197 and connected parts upon the yoke 206 125 brings the nostril 210 into contact with the upper side of the band at 49^b. When this occurs, the cam 48 acting upon the right roller 47, moves the piston 42 toward the right and thus creates a partial vacuum within 130

the cylinder 39 which communicates with the nostril 210 and thus the pressure of the atmosphere upon the lower side of the band presses said band against said nostril. The 5 wall of the cam groove 190 acting through the roller 189 and connected parts upon a movable member 170 of the depositor clamp lifts said member from contact with the band and as soon as this occurs, the wall of the 10 cam groove 151 then moves the depositor to bring the clamping end of the fixed member 169 to the position shown, dotted in Fig. 1, the cam groove 190 acting through the roller 189 and connected parts keeping the movable member 170 raised from the fixed member 169.

It is to be noted that during the movements of the depositor the springs 161 and 20 163 act as cushions to absorb the shocks due to the inertia of the parts.

While I have shown a rotatory conveyer provided with clamps thereon for holding the article to be wetted, a wetting mechanism and a depositor for removing the article 25 from the clamps on the conveyer in combination with means for varying the time interval between the wetting of the article and the removal of the article from the clamps of the conveyer by the depositor, it 30 is to be understood that my invention is not limited to the use of a rotatory conveyer, for the means for varying said time interval or the equivalent thereof may be used with many forms of conveyers and many forms of 35 depositors. Furthermore, while I have shown one specific means for periodically wetting one side of the sponge forming part of my wetting mechanism, it is to be understood that many forms of mechanisms may be provided for accomplishing this purpose and 40 the variation in the aforesaid time interval without departing from the spirit of my invention.

It is also to be noted that many changes 45 may be made in the space relations of the elements of my improved coating machine and in the correlation of the movements thereof without departing from the spirit of my invention.

50 I claim:—

1. In a coating machine, the combination with a conveyer, of a plurality of clamps thereon, means for opening each of said clamps to receive an article, means for closing said clamps, a depositor for moving an article from each clamp and means for opening each clamp to deliver an article to said depositor, said means also acting to open a plurality of adjacent clamps in order 55 to provide clearance for said article during its movement by said depositor.

2. In a coating machine, the combination with a conveyer, of a plurality of clamps thereon, means for opening each of said clamps to receive an article, means for closing said clamps, a depositor, said depositor comprising fixed and movable clamp members, means for moving said movable member away from said fixed member, means for moving said article between said members, means for moving said movable member to grasp said article, means for opening said clamp, means for moving said depositor into position to deliver said article and means for moving said movable member to release said article. 65 70 75

3. In a coating machine, the combination with a conveyer for articles to be wetted, a plurality of clamps thereon for clamping said articles and a depositor comprising 80 clamping members, of timed mechanism for opening and closing said clamps and clamping members to deliver said articles from said clamps to said clamping members.

4. In a coating machine, the combination with a conveyer for articles to be wetted, a plurality of clamps thereon for clamping said articles, mechanism for delivering an article to each clamp and a depositor comprising clamping members, of timed mechanism for opening and closing said clamps and clamping members to deliver said articles from said clamps to said clamping members and mechanism for removing said article from said clamping members. 85 90 95

5. In a coating machine, the combination with a conveyer and means for imparting rotatory motion thereto in a plurality of steps alternating with dwells, of a yieldable clamp for holding an article mounted on said conveyer, a depositor, and means for releasing said article from said clamp and delivering it to said depositor during a dwell. 100

6. A coating machine comprising a movable conveyer and a movable depositor, each provided with means to clamp an article, means acting to deliver said article from the clamps on said conveyer to the clamps on said depositor, means acting to deliver 105 said article to the clamp on said conveyer and means acting to remove said article from the clamp on said depositor.

7. In a coating machine, the combination with a conveyer, of a clamp thereon and means for delivering a band to said clamp so that said clamp will grasp said band only near the centre thereof. 115

In testimony whereof I affix my signature.

REINHOLD D. SCHOENWETTER.
